UNITED STATES PATENT OFFICE

HARRY W. LASTER, OF OAK PARK, ILLINOIS, ASSIGNOR OF ONE-HALF TO JOSEPH W. SCHINDLER, OF ELMHURST, ILLINOIS

SCARIFYING ATTACHMENT FOR PAVING ROLLERS

Application filed February 7, 1930. Serial No. 426,459.

This invention relates to scarifying attachment for paving rollers, and its principal object is to provide improved mechanism propelled by a powerful machine, such as a street paving roller, for tearing up the surface portion of macadamized streets or roads. Another object is to provide a scarifying attachment with rotating means for loosening the surface portion of the pavement, combined with other means for tearing the surface portion of the pavement away from the part therebelow.

It further consists in a scarifying attachment, as above set forth, in which the scarifying implements are forced down upon the pavement by a ram or other engine operated by steam or other expansible fluid.

With these and other objects and advantages in view, this invention consists in the several novel features hereinafter fully set forth and claimed.

The invention is clearly illustrated in the drawings accompanying this specification in which—

Figure 1 is a side elevation of a conventional street paving roller, partly broken away, equipped with a scarifying attachment embodying a simple form of the present invention;

Fig. 2 is a plan of the paving roller, partly broken away, and the scarifying attachment;

Fig. 3 is an enlarged detail vertical longitudinal section of the scarifying attachment taken on the line 3—3 of Fig. 2; and

Fig. 4 is a perspective view of fragments of the tooth supporting member, a tooth and a locking bar.

Referring to said drawings, the reference character 5 designates a street paving roller of conventional form having the usual steering roll 6 and traction roll 7. Usually a steam boiler 8 is provided for supplying steam to the engine 9 which drives the roller. Street paving rollers are common and well known, and it is believed that no further description of the one shown is required so far as this specification is concerned.

Fulcrumed on a line co-axial with the axis of the traction roll 7 is the scarifying structure which comprises, in part, longitudinally

extending side frame members 10. Rotatably mounted in bearing blocks secured on said side frame members 10 is a shaft 11 upon which are rigidly mounted two spiked rollers 12. Said spiked rollers 12 are positively driven from the traction roll 7 by gearing, here shown as comprising a sprocket wheel 13 connected to said traction roll 7, and a sprocket wheel 14 mounted upon a counter-shaft 15 journaled in bearing blocks carried by the side frame members 10. A sprocket chain 16 is trained around said sprocket wheels 13 and 14 and another sprocket chain 17 is trained around sprocket wheels 18 and 19, one of which is rigidly mounted upon the counter-shaft 15 and the other upon the shaft 11.

The spikes of the spiked roller 12 are shown at 20 and comprise sturdy spike members rigidly secured on the face of the roller. Preferably the sprocket wheel 19 is placed at the middle of the shaft 11 and the two spiked rollers 12 are placed at the sides of the sprocket wheel. With this arrangement, the power is applied at the middle of the shaft and transmitted to the rollers at either end thereof.

The gear ratio of said gearing is such that the lineal feet of travel of the spiked rollers 12 is somewhat greater than that of the traction roll 7. The purpose of this increased speed of travel of the spiked roller above that of the traction roll is to enable the spiked roller to assist the traction roll in propelling the machine as well as to tear up the surface portion of the pavement.

Mounted upon the rear end of the supporting bars or side frame members 10 is the scarifier 21. The scarifier is adjustably mounted on the side frame members so as to regulate the depth of cut made by its teeth. The teeth 22 of the scarifier are in the form of square bars pointed at both ends, and said teeth are adjustable lengthwise in their support for purposes of adjustment, as will appear later.

A supporting head 23 formed of a solid block of material is rotatably mounted on a shaft 24 secured in the free ends of the side frame members 10 as by nuts or the like.

The ends of the head 23 are formed with ears 25 through which the shaft 24 extends, and projecting up from said ears are lugs 26 through which extend adjustment studs 27 that bear against shoulder blocks 28 bolted or otherwise fastened to the upper edges of the side frame members 10. By turning the adjustment studs 27, the head 23 may be partially rotated upon the axis of the shaft 24, thereby changing the angular position of the teeth 22, and, as a consequence, increasing or decreasing the depth at which they will engage the pavement.

The head 23 is formed with a plurality of square openings 29 therethrough which extend at an oblique angle, and in said openings are received the teeth 22. In order to provide for the longitudinal adjustment of the teeth 22 in the head 23, the teeth are formed with spaced notches 30 in their side edges and the head 23 is formed with a lengthwise extending groove 31 in its upper face with which any of the notches in the teeth may be made to register, and a locking bar 32 is provided which is placed in the groove 31 and in the notches of the teeth that have been adjusted into registry with the groove.

When the bar is placed in the groove and registering notches, it effectively locks the teeth to the head and provides a very sturdy and rugged connection therebetween which is very essential because of the rough usage to which a machine of this character is put. For securing the locking bar in place, a plurality of studs 33 may be provided in the head 23 in position to extend through openings in the locking bar, and nuts 34 are provided upon the studs for engaging with the locking bar.

It is to be observed that the head 23 may be adjusted to bring the teeth 22 into any desired angle of inclination and the teeth may thus be raised or lowered somewhat to bring their effective ends into position for making the desired cut. Furthermore, in case it is desired to make a deeper or shallower cut than can be obtained by adjusting the head, the locking bar 32 may be detached and the teeth 22 drawn out of the openings 29 and turned to bring the proper notches into register with the groove 31, so as to obtain the proper adjustment after which the locking bar 32 may be again secured in place, thereby securely locking the teeth in the head.

Power operated means is provided for depressing the supporting element for the spiked rollers and scarifier, and, as shown, said device comprises a ram 35 mounted upon some stationary portion of the paving roller and having a piston rod 35^a connected to the supporting element for the spiked rollers and scarifier. As shown, the connection between the piston rod and supporting element comprises a rod or bar 36 mount-

ed in brackets 37 secured to the side frame members. The piston rod is provided with a sleeved member on its lower end which encircles the rod or bar 36.

When used in connection with a steam paving roller, the ram 35 may be supplied with steam from the boiler of the paving roller and suitable control mechanism (not shown) may, of course, be provided for governing the admission of the steam to the cylinder of the ram. Inasmuch as the supporting element for the spiked roller and scarifier is movable upon a fulcrum, the ram is also fulcrumed upon the paving roller to permit it to oscillate thereon and thereby accommodate itself to any changes of angularity between the supporting element and cylinder of the ram.

The ram operates to depress the scarifier structure and means are provided for limiting the downward movement of the latter. Said means comprises, as shown, a pair of heavy chains 38 secured to the brackets 37 and to some stationary part of the paving roller. Turn buckles, or other threaded connections, 40 are provided in connection with the chains, whereby the position of the scarifying structure may be regulated to obtain the desired penetration of the spikes 20 into the pavement. It is to be observed that the ram 35 operates to force the scarifying structure in a downward direction, which action is limited by the length of the chains. As a result, the amount of penetration of the spikes into the surface portion of the pavement can be regulated to suit the peculiar conditions of the pavements.

In the operation of the apparatus, the proper adjustments are made with the chains 38 and turnbuckles 40 and with the scarifying head 23 and its teeth 22. The paving roller is driven over the pavement to be operated on and steam is admitted to the ram, thereby forcing the scarifying structure down to the limit allowed by the chains. Inasmuch as the spiked rollers 12 travel at a greater surface speed than the traction roll of the paving roller, the spiked rollers not only act to tear up the surface portion of the pavement, but also aid the traction roll in propelling the machine along the pavement. The teeth of the scarifier follow the spiked rollers and rip off the surface portion of the pavement to a depth determined by the lower ends of the teeth.

It is to be observed that the paving roller may be used for rolling down pavements in the usual manner, and when so used, the scarifying attachment is raised above the surface of the pavement so that it will not interfere with the operation of the paving roller.

The ram operated scarifying supporting element may be used for other purposes than for supporting the spiked rollers and scari-

fier. For instance, a grooved paving roller, such as is shown and described in my application for patent on paving rollers, filed March 13, 1929, under Serial No. 346,537, may be used in place of the spiked rollers when rolling pavements. The change may be made very quickly, thus enabling the machine to be used for scarifying pavements and for rolling them.

I claim as new, and desire to secure by Letters Patent:

1. A scarifying attachment for paving rollers comprising a supporting element arranged for attachment to a paving roller, a spiked roller and a scarifier mounted on said supporting element, power operated means for rotating said spiked roller, and a ram connected to said supporting element and operating to depress the same and therewith the spiked roller and scarifier.

2. A scarifying attachment for paving rollers comprising a supporting element arranged for attachment to a paving roller, a spiked roller and a scarifier mounted on said supporting element, power operated driving means for rotating said spiked roller, a ram supported by said paving roller and connected to said supporting element and operating to depress the same and therewith the spiked roller and scarifier, and means for limiting the downward movement of said supporting element.

3. A scarifying attachment for paving rollers comprising a supporting element arranged for attachment to a paving roller, a spiked roller and a scarifier mounted on said supporting element, power operated driving means for rotating said spiked roller, a ram supported by said paving roller and connected to said supporting element and operating to depress the same and therewith the spiked roller and scarifier, and lengthwise adjustable chain connections between said paving roller and supporting element for limiting the downward movement of the latter.

4. The combination with a paving roller having a traction roll, a supporting element fulcrumed on the axis of said roll, a spiked roller and a scarifier mounted on said supporting element, gearing between said traction roll and the spiked roller, and a power element interposed between the paving roller and supporting element for depressing the latter and therewith the spiked roller and scarifier.

5. The combination with a paving roller having a traction roll, a supporting element fulcrumed on the axis of the traction roll, a spiked roller and a scarifier mounted on said supporting element, chain drive gearing between said traction roll and the spiked roller, a ram mounted upon the paving roller and operatively connected with said supporting element, and adjustable connections between

said paving roller and the supporting element for limiting the downward movement of said supporting element.

6. A scarifying attachment for paving rollers comprising a supporting element having two side frame members arranged for attachment to a paving roller, a shaft rotatably mounted in said side frame members, a sprocket wheel mounted in the middle of said shaft, sprocket chain connections between said sprocket wheel and a power driven member of the paving roller, a pair of spiked rollers mounted on said shaft between said side frame members, one spiked roller on either side of the sprocket wheel and rigidly secured to said shaft, and a ram interposed between the paving roller and the supporting element and operating to depress said supporting element and therewith the spiked rollers.

7. In a scarifying attachment for paving rollers, the combination of a pair of supporting bars, arranged for attachment to a paving roller, a crosswise extending rod secured in one end of said bars, a tooth supporting head extending between said supporting bars and having ears on its ends through which said rod extends, teeth mounted in said head, and adjustment studs carried by said ears and arranged to engage shouldered members carried by the supporting bars.

8. In a scarifying attachment for paving rollers, the combination of a pair of supporting bars, arranged for attachment to a paving roller, a crosswise extending rod secured in one end of said bars, a tooth supporting head extending between said supporting bars and having ears on its ends through which said rod extends, teeth mounted in said head for longitudinal adjustment therein, and adjustment studs carried by said ears and arranged to engage shouldered members carried by the supporting bars.

9. In a scarifying attachment for paving rollers, the combination of a pair of supporting bars, a tooth supporting head mounted thereon, said head being formed with parallel openings extending transversely therethrough and a groove in one face intersecting said openings, teeth extending through said openings, said teeth being formed with spaced notches in their sides, any of which is arranged to be brought into register with said groove, a locking bar adapted to be let into said groove and the notches registering therewith, and means for securing said locking bar in place.

10. In a scarifying attachment for paving rollers, the combination of a pair of supporting bars, a tooth supporting head mounted thereon, said head being formed with parallel square openings extending transversely therethrough and a groove in one face intersecting said openings, teeth in the form of square bars extending through said square

openings, said teeth being formed with spaced notches in their sides, any of which is arranged to be brought into register with said groove, a locking bar adapted to be let into said groove and the notches registering therewith, and means for securing said locking bar in place.
